UNITED STATES PATENT OFFICE.

LEWIS T. WILCOX, OF PEEKSKILL, NEW YORK.

HEAT COLLECTOR.

Application filed February 19, 1927. Serial No. 169,446.

In many types of liquid fuel or gas burning cooking stoves in which there are a plurality of cooking holes in the top or key-plate, it is desirable to cause a single burner 5 to supply heat to two or more holes. This is accomplished as a rule by situating the burner in register with one hole and providing means to conduct the heat from that hole underneath the key-plate to the other hole or 10 holes to be served by the same burner. Such means are commonly termed heat collectors and it is to such devices that this invention relates. The collector functions in combination with the stove top when the holes are 15 closed by cooking utensils or otherwise, and also with a suitable grate in the remote opening to collect substantially all the heat from the burner and pass it first in efficient heating relation to the utensil on the immediate 20 hole and thence conduct it with a minimum of loss to efficient heating relation to the utensil on the remote hole. That combination forms the subject matter of another co-pending application, Serial No. 170,756. 25 This application is confined to the features peculiar to the heat collector itself, which make it especially adapted for its purpose.

The heat collector which forms the subject matter of this application is characterized by the fact that it approximates the shape of an elongated tray which has a plane top and is relatively shallow at its ends and grows deeper toward the middle, being deepest in its transverse center line. The one 35 end which is termed the front end has a large opening in the sloping bottom which in use is over the burner and in register with the first cooking hole, while at the other end the oppositely sloping bottom is imperforate. Both 40 ends are rounded and the side walls are brought in at the center so as to constrict the width where the depth is greatest. The device is economically stamped from sheet metal, in which case it is provided with a 45 down-turned strengthening flange around its outer edge to prevent warping from the heat. Suitable holes in the top adapt it for attachment to the stove top. There are other details of its construction which are of merit 50 that will appear from the following description of one embodiment of the invention as shown in the drawings, in which:

Fig. 1 is a longitudinal section through the center of a heat collector constructed in 55 accordance with this invention and applied to an oil stove;

Fig. 2 is a plan view of one end section of a stove having this invention embodied therein;

Fig. 3 is a section on line 3—3 of Fig. 1, 60 and

Fig. 4 is a perspective view of the heat collector constructed in accordance with this invention.

Referring particularly to Fig. 4 there is 65 shown a heat collector preferably of sheet steel constructed in accordance with this invention and comprising an oblong tray-like member, the entire center portion of which is depressed forming a dish-like structure 70 leaving a narrow horizontal flange 1 around the outer edge thereof and having a bottom 2 which inclines downwardly from each end toward the center, the rear end being inclined more steeply than the front end. 75 The side walls 3 of the depression are substantially vertical and at the end portions define two somewhat circular chambers 4 and 5 one at each end of the tray. The two side walls converge toward each other at the 80 center portion of the tray as at 6 and form a narrow passage 7 connecting the two end chambers 4 and 5.

The front end of the tray-like members has a circular opening 8 through the bottom 85 thereof to permit the heat emerging from the upper end of a burner to enter the heat collector. The edge of the opening 8 is flared upwardly as at 9 to aid in collecting the rising heat. The radius of curvature of the side 90 wall of the front chamber 4 increases at the sides thereof so that the front chamber has an increasing diameter with its maximum diameter at the sides thereof. It is to be noted that although the opposite side walls 95 converge at the center portion the depth of the tray at the center is greater so that the cross sectional area is equal to the maximum at the center and there is no restriction to the flow of heat but merely a lowering of 100 the mean level. The outer periphery of the tray is bent downwardly to form a depending stiffening and strengthening flange 10 which also serves to prevent the collector 105 from warping when subjected to heat. The top horizontal surface may be bored as at 11, at the four corners to secure the collector to a key-plate or stove top.

In Figs. 1, 2 and 3 an embodiment of this invention is shown as applied to an oil stove 110 having a top frame 12 supporting a key-plate or stove top 13 to which is attached a col-

lector constructed in accordance with this invention.

The key-plate has two openings therein one directly over the burner 14 which supplies the heat and another positioned rearwardly and removed from the burner, the two openings being positioned directly over the chambers 4 and 5 of the heat collector. The front opening has a flush grid 15 therein, whereas the rear opening which is supplied from the same source of heat, namely, burner 14, has a special grid or grate 16 thereover constructed in accordance with that disclosed in my application Serial No. 15 170,756.

The flow of heat is particularly indicated by arrows in Figs. 1 and 2 from which it can be seen that as the heat rises from the burner it enters the front chamber of the heat collector and strikes the key-plate, the curved sides of the chamber and the bottom of a vessel supported over the front opening, and is thereby deflected and drawn rearwardly by the draught through the collector. The front chamber 4 being larger as it recedes rearwardly, it readily permits an increasing volume of heat to be collected and conducted rearwardly. As the heat passes through the center portion of the collector the mean level is lowered due to the sloping bottom and narrowed sides, but its flow is not restricted inasmuch as the cross sectional area is not decreased. The heat then flows from the lowest point up into chamber 5 and through the rear grate being aided in its upward movement by the rear upwardly sloping bottom of chamber 5.

It is to be noted that the front upper end of burner 14 is slightly below the edge of the bottom of the collector thereby permitting the hot gases of any accidental flare-back to escape forwardly and out without coming directly up through the two openings in the stove top.

It follows therefore that a heat collector as shown and described will collect substantially all of the heat from a single burner and apply it in a most efficient manner to two openings by reason of the unrestricted duct which guides and increases the flow of the heat.

It is obvious that minor changes may be made in the structure disclosed without departing from the spirit and scope of this invention as defined in the appended claims.

I claim:

1. A heat collector for stoves comprising a dish-shaped tray member deeper at its center portion than at its end portion, one 60 of said end portions having an opening in the bottom thereof for the admission of heat and the other of said ends having an imperforate bottom.

2. A heat collector for stoves comprising 65 a dish-shaped tray member deeper and nar-

rower at its center portion than at its end portion, one of said ends having an opening in the bottom thereof for the admission of heat and the other of said ends having an imperforate bottom. 70

3. A heat collector for stoves comprising a dish-shaped tray member deeper and narrower at its center portion than at its end portions, one of said ends being deeper than the other and having an opening in the bottom thereof for the admission of heat and the other of said ends having an imperforate bottom. 75

4. A heat collector for a stove comprising a dish-shaped tray member having a bottom wall which slopes from the center portion upwardly toward each end, one of said sloping portions having an opening therethrough to permit the entry of heat and having two chambers joined at the center portion of the tray by a relatively narrow passage. 80

5. A heat collector for a stove comprising a dish-shaped tray member having a bottom which is inclined from the center portion 90 upwardly to the end portions, one of said end portions having an opening therethrough to permit the entry of heat and having two substantially circular chambers, one at each end of the tray joined at the 95 center portion of the tray by a transversely narrowed center passage, the radius of curvature of the circular chamber associated with the end having an opening therethrough being greater at the sides than at 100 one end thereof.

6. A heat collector for stoves comprising a dish-shaped tray member having a substantially circular depression at each end thereof, the bottom walls of which incline downwardly toward the center portion of said member, the side walls of which converge at the center portion, one of said depressions having an opening therethrough adapted to permit admission of heat, the periphery of said tray-like member having a strengthening flange therearound to prevent warping of said tray member. 105

7. A heat collector for use with cooking stoves comprising a tray-shaped member for attachment to the under side of a stove top and adapted to enclose two cooking holes and having a bottom sloping from both ends downwardly to the transverse middle line and provided with a burner opening in one 115 of the sloping bottom portions.

8. A heat collector for use with cooking stoves comprising a tray-shaped member for attachment to the under side of a stove top and adapted to enclose two cooking holes and having a bottom sloping from both ends downwardly to the transverse middle line and provided with a burner opening in one 125 of the sloping bottom portions, said tray also having formed therein two chambers in 130

the end portions joined by a relatively narrow passage through the center portion of the tray.

9. A heat collector for use with cooking stoves comprising a tray-shaped member for attachment to the under side of a stove top and adapted to enclose two cooking holes and having a bottom sloping from both ends downwardly to the transverse middle line and provided with a burner opening in one of the sloping bottom portions, said tray also having formed therein two chambers in the end portions joined by a relatively narrow passage through the center portion of the tray, said chambers being substantially circular and of greater diameter than said cooking openings.

10. A heat collector for use with cooking stoves comprising a tray-shaped member for attachment to the under side of a stove top and adapted to enclose two cooking holes and having a bottom sloping from both ends downwardly to the transverse middle line and provided with a burner opening in one of the sloping bottom portions, said tray also having formed therein two chambers in the end portions joined by a relatively narrow passage through the center portion of the tray, the outer periphery of said tray being formed with an angularly bent stiffening flange.

11. A heat collector for stoves comprising a sheet metal tray-shaped member, the depression in the ends being of substantially circular shape and connected by a narrowed

passage, one end having an opening in its bottom for the admission of heat and the other end having an imperforate bottom sloping upwardly from the connecting passage, and the depression being of maximum depth at the beginning of said sloping bottom.

12. A heat collector for stoves comprising a sheet metal single walled tray-shaped member having a depression with substantially circular ends connected by a narrowed passage, the bottom of one end being open and the other imperforate, the sheet metal being flanged laterally from the top edge of the depression to form a flat top face about the depression and having its extreme edge flanged downwardly and forming a strengthening flange to prevent warping of the tray member.

13. For cook stoves and the like a combined stove top part and heat collector, both being formed of sheet metal and the stove top part including two cooking holes and the heat collector being disposed underneath the stove top part and coupling the two holes and being of a shape approximating the figure 8 and being relatively deep at the restricted central connecting part and having the bottom at one end provided with a burner opening and the bottom at the other end imperforate and sloping up from the restricted connecting part.

In witness whereof, I hereunto subscribe my signature.

LEWIS T. WILCOX.
